UNITED STATES PATENT OFFICE

GUSTAVE H. JANTZ, OF WYOMING, OHIO

WRINGER

Application filed August 7, 1929. Serial No. 384,145.

My invention relates to wringers of the character of those employing opposite wringer rolls between which the goods are arranged to be passed for expressing the water, and my present invention is an improvement upon the device shown, described and claimed in my Letters Patent No. 1,408,807, for wringer, dated March 7, 1922.

In the wringer shown and described in 10 the aforesaid patent the latching means are in the inside of the frame and closely adjacent to the pivot of the movable part of the wringer frame.

It is the object of my invention to construct 15 the frame of the wringer in a plurality of parts each of which has a wringer-roll mounted thereon, and to provide means for pivoting one frame-part on the other frame-part at one side of the wringer-rolls, and means 20 for latching one frame-part to the other frame-part at the other side of the wringer-rolls.

It is the object of my invention further to 25 provide novel spring means for causing latching between the frame-parts and novel releasing means for the latching means operable in opposite directions for releasing the movable frame-part and thereby causing separation between the wringer-rolls.

30 It is the object of my invention further to place the actuating parts of the releasing means which coat with the latch at one side of the wringer frame and to provide a spring latch which is movable at the outside of the frame and substantially conceals said coacting parts.

The invention will be further readily understood from the following description and 35 claims, and from the drawings, in which latter:

Fig. 1 is a front elevation of my improved device, partly broken away.

Fig. 2 is a plan view of the same, partly 40 broken away.

Fig. 3 is a rear view of the same, partly 45 broken away.

Fig. 4 is an end view of the same.

Fig. 5 is a cross-section of the same, taken 50 on the line 5—5 of Fig. 1.

Fig. 6 is a longitudinal section of the

same, taken on the line 6—6 of Fig. 2, and partly broken away.

Fig. 7 is a detail sectional view, taken in the plane of the line 7—7 of Fig. 5; and,

Fig. 8 is a front view of one end of my improved device, partly broken away.

The lower or base section of the frame is exemplified at 11, and may be provided with any suitable means for attaching the wringer to a support, for instance a tub or a power washing machine. The lower frame-section is exemplified as built up of sheet metal and comprises end pedestals 12, each of which has an upright channel 13 therein, in which there is a shelf 14. A lower bearing 15 is located in each of these upright channels on said shelf.

The shaft 18 of the lower wringer-roll 19 is received in bearing recesses in the bearings. These bearing recesses are open upwardly so that the wringer-roll with its shaft may be readily lifted out of the bearings and removed from the wringer or be readily replaced therein.

The shaft 18 is provided with suitable turning means at its end, which may be either arranged for manual or for power operation. I have shown the end of the lower wringer-roll provided with a tongue 21 which may be received in the socket of a suitable power driven member of power driving means for 55 rotating the shaft.

An upper wringer-roll 25 coacts with the lower wringer-roll and is mounted on a shaft 26. The shaft 26 is journaled in bearings 27 at its respective ends. The bearings 15 and 27 may be blocks of treated wood, treated for reducing friction. Each of the bearing blocks 27 is received in a strap 28 which is received about the top and sides of the block and has lips 29 at the bottom of the block. This strap is open-ended for endwise removal of the bearing.

The straps are adjustable up and down in yokes 31 at the respective ends of the machine. The yokes are connected by a connecting bar 32, which is rigidly connected with the respective yokes, as by screws 33.

Adjusting screws 34 are adjustable in threaded bearings 35 in the respective yokes. The adjusting screws have swivel connection

with the respective straps. Each of the adjusting screws has a ball 36 at its lower end which is received in a complementary socket 37 formed in the upper portion of the strap.

5 Each of the adjusting screws is provided with a knurled head 38 for turning the same.

The upper wringer-roll is arranged to be driven from the lower wringer-roll, as by providing the respective wringer-rolls with 10 toothed driving sections 41, 42, for instance as shown, described and claimed in my Patent No. 1,516,886, for wringer roll dated November 25, 1924.

Means are provided for permitting instant 15 separation between the wringer-rolls to prevent accident to the goods or to the operator, or to relieve pressure between the wringer-rolls in case of accident, or to prevent injury to the operator upon accidental catching of 20 the fingers or clothes of the operator between the wringer-rolls and for providing separation between the wringer-rolls for other purposes.

For accomplishing the objects mentioned I 25 have preferred to divide the frame of the wringer into frame-sections which support the respective opposed wringer-rolls, forming what I term a break-down frame, and to provide means whereby the pressure mechanism 30 which causes pressure between the wringer-rolls while the goods are passing therebetween is part of one of the frame-sections.

I have provided springs 46 for exerting 35 pressure between the wringer-rolls. These springs are interposed between the two parts of the movable section of the wringer-frame. One of these movable parts is pivoted to the relatively stationary or base section of the 40 wringer-frame hereinbefore described, and the other of these parts is arranged to support the upper wringer-roll 25.

The lower frame-section is provided with pivot-lugs 47 and the upper frame-section 45 comprises pivot-parts 48 from which pivot-lugs 49 extend. Pivot-screws 50 are received in the pivot-lugs 47, 49, at the respective ends of the machine for pivoting the upper frame-section to the lower frame-section.

50 The springs 46 are shown as bow-springs with the ends of the bows of the respective springs adjacent to each other. The lower leaves 53 of the respective bow-springs are fixed to the respective pivot-parts 48, as by 55 rivets 54, at points distanced from the ends of said leaves, leaving extensions 55 of said leaves which extend forwardly from said pivot portions and are located between the shafts of the coacting wringer-rolls and are 60 provided with catching portions 56 at their forward ends, preferably having lower bevel faces 57.

The yokes 31 are provided with rearwardly extending lugs 58 to which the forward ends 65 of the upper leaves 59 of the bow-springs are

respectively fixed, as by means of rivets 60.

A spring latch is provided at each end of the lower frame-section for coaction with the catch at the forward end of each of the lower leaves of the bow-springs, for holding the upper frame-section in operative relation with the lower frame-section, and holding the wringer-rolls in operative relation with each other, with pressure between the rolls for wringing the clothes.

75 Each of the latches is shown as comprising a keeper 64 having an upper bevel-face 65, with which the lower bevel-face 57 on the catch at the forward end of the lower leaf of the bow-spring coacts. The keeper is at the upper end of a leaf-spring 66, the lower end of which is secured to the lower frame-section, as by screws 67 received through the leaf-spring and threaded into the front wall of the lower frame-section.

80 One of these leaf springs extends upwardly along the front wall of the upwardly extending pedestal or pillar of the lower frame-section at each end of the lower frame-section. The resilience of the leaf-spring 90 presses the latches toward the wringer-rolls and toward the catches when the latter are in latching position, the latches being normally resiliently pushed forwardly by the catches when swinging the upper frame-section on its pivots for engagement of the catches under the latches, the latches rebounding above the catches when the latter have been forced downwardly to sufficient extent.

85 100 This connection between the catches and the latches is preferably accomplished by a quick snap movement of the upper frame-section into working position, as by grasping the bow portions of the bow-springs in the hands and imparting a quick pivotal movement of the upper frame-section about its pivots, or pressing downwardly on the yoke members or connecting bar of the upper frame-section for engaging the catches under 105 the latches.

110 I provide quick releasing means for the latches, shown comprising a lever 71 at each end of the frame. Each of these levers is pivoted by a pivot 72 to the lower frame-section at the respective ends of the lower frame-section. The lower ends of the levers are received inside the outer walls 73 of the pedestals 12 at the respective ends of the machine. The pivot is shown in the form of a bolt received through a pivot-hole 74 in each of the levers, the lever being located between the head 75 of the pivot-bolt and the inner face of the outer wall 73. A nut 76 is threaded over the outer end of the pivot-bolt for holding the pivot-bolt in place.

115 120 125 A cross-bar 79 is secured to the upper ends of the levers 71 for connecting the levers. These connections are preferably rigid for causing combined movements of the levers 130

and simultaneous release of the latches at the respective ends of the wringer. The cross-bar is provided with a reduced end 80 at each of its ends, received through holes 5 in the upper end of the levers, nuts 81 screwed about the threaded reduced ends clamping the levers to the bar.

Each of the levers is provided with contact-lugs 82, 83, arranged to contact respectively with a contact-lip 84 extending from the leaf-spring 66. The contact-lugs extend through a slot 85 in the front wall of the pedestal. The leaf-spring and its contact-lip extend laterally across the pedestal and 15 across said slot to hide the slot and prevent the catching of clothes therein. A substantially closed structure is thus provided for hiding and protecting the latch releasing parts and for removing these parts from contact by the clothes.

The respective lugs 82, 83, are respectively above and below the pivot 72, so that forward movement of either of said lugs acts to release the latch, at each end of the machine. The 25 lower portion 86 of each of the levers 71, in which the pivot 72 and the lugs 82, 83, are located, is at the forward side of the shafts of the wringer-rolls, and distanced from the pivots of the movable frame-section, which 30 are at the other side of the wringer-rolls. Each of the levers is preferably provided with a rearwardly extending portion 87 at a point between the wringer-rolls, from which an upwardly extending portion 88 extends. This upwardly extending portion is 35 preferably in the vertical plane parallel with the wringer-rolls in which the shafts of the wringer-rolls are located.

This provides a compact construction, and 40 provides convenient placing of the upper ends of the levers and the upper cross-bar connecting the levers for movement thereof either forwardly or backwardly for the prevention of accident. A pushing or pulling upon the 45 cross-bar 79 or the exposed portion of either of the levers 71 causes pressure of one of the lugs 82, 83, at each end of the machine against the spring latches for instantly releasing said spring latches by a short movement of the 50 cross-bar, for releasing the pressure between the wringer rolls and causing quick separation between them by the upward swinging of the upper wringer-roll on the pivots of the upper movable frame-section.

55 When the cross-bar 79 is pulled or pushed forwardly by the operator, the upper lugs 82 move the spring latches for releasing the upper frame-section, and when the upper cross-bar 79 is moved rearwardly by the 60 operator, the lower lugs 83 move the spring latches for releasing the upper frame-section. This movement of the releasing means is 65 readily accomplished by the operator by mere pushing or pulling contact with the upper ends of the levers or cross-bar without the

necessity of grasping any of these parts by the hand.

The pressure between the wringer-rolls may be adjusted by adjusting the adjusting screws 34 and thereby adjusting the bearings 70 of the upper wringer-roll in the yokes 31 toward and away from the lower wringer-roll.

The release movement of the upper wringer roll may be limited by providing the pivot-lugs 49 with projections 91, which form stops 75 arranged to contact the pedestals 12, when the upper wringer-roll is swung rearwardly upon release of the latches 65.

My improved device is especially simple and effective for the purposes described, and 80 is compact, economical in construction and durable.

Having thus fully described my invention, what I claim as new, and desire to secure by Letters Patent, is:

1. In a wringer, the combination of a breakdown frame for the wringer comprising a plurality of frame-parts each including bearing means for a wringer-roll, wringer rolls comprising shafts in said bearing means, 90 pivot means between said frame-parts whose pivotal axes are substantially parallel with the axes of said bearing means, one of said frame-parts comprising bow-springs as part of its frame structure for exerting pressure 95 between said wringer-rolls, said bow-springs located between said pivot means and said bearing means for said one of said frame-parts, said pivot means being at one side of said wringer-rolls, said second-named frame section 100 provided with extensions reaching between and beyond the other side of said shafts where they are provided with catching means, latching means at said other side of said wringer-rolls coacting with said catching 105 means for holding said frame-parts in operative relation, and quick releasing means for said latching means for quick release of said latching means from said catching means for quick separating movement between said 110 wringer-rolls.

2. In a wringer, the combination of a frame-section, a wringer-roll mounted therein, a second frame-section, a wringer-roll mounted therein, said wringer-rolls comprising shafts, pivots between said frame-sections at one side of said wringer-rolls, said second-named frame-section comprising bow-springs between said pivots and said second-named wringer-roll, said second-named frame-section provided with extensions between and beyond said shafts of said wringer-rolls, latching means at the other side of said shafts between said extensions and said first-named frame-section, and quick releasing means 115 comprising releasing parts at the respective ends of said wringer and located at said other side of said shafts, said quick releasing means coacting with said latching means and comprising a manipulating part connecting said 120 125 130

- releasing parts at the respective ends of said wringer, and said manipulating part comprising arms at said respective ends extending upwardly between said pivot means and said latching means.
5. In a wringer, the combination of a lower frame-section comprising bearing means for a lower wringer-roll, an upper frame-section comprising bearing means for an upper wringer-roll and bow-springs for said last-named bearing means formed as part of the frame structure of said upper frame-section, said bow-springs comprising upper leaves and lower leaves, wringer-rolls comprising shafts in said bearing means, pivot means between said lower frame-section and said bow-springs having connections with said bow-springs distanced from the ends of said lower leaves forming extensions of said lower leaves, said upper leaves supporting said second-named bearing means, said pivot means located at one side of said wringer-rolls and said extensions extending between and beyond said shafts, latching means coacting with the free ends of said extensions at the other side of said wringer-rolls, and quick release means for said latching means.
4. In a wringer, the combination of a lower frame-section comprising bearing means for a lower wringer-roll, an upper frame-section comprising bearing means for an upper wringer-roll and bow-springs for said last-named bearing means formed as part of the frame structure of said upper frame-section, pivot means between said lower frame-section and said bow-springs having connections with said bow-springs distanced from the ends of said lower leaves forming extensions of said lower leaves, said upper leaves supporting said second-named bearing means, adjusting means for adjusting the distance between said upper bearing means and said lower bearing means, said pivot means located at one side of said wringer-rolls and said extensions extending between and beyond said shafts, latching means coacting with the free ends of said extensions at the other side of said wringer-rolls, and quick release means for said latching means.
5. In a wringer, the combination of a break-down frame for the wringer comprising a plurality of frame-parts each including bearing means for a wringer-roll, wringer-rolls comprising shafts in said bearing means, pivot means between said frame-parts whose pivotal axes are substantially parallel with the axes of said bearing means, one of said frame-parts comprising bow-springs as part of its frame structure for exerting pressure between said wringer-rolls, said bow-springs located between said pivot means and said bearing means for said one of said frame-parts, said pivot means being at one side of said wringer-rolls, said one of said frame-parts pro-
- vided with extensions reaching between and to the other side of said shafts where they are provided with catching means, latching means at said other side of said shafts coacting with said catching means for holding said frame-parts in operative relation, quick releasing means for said latching means for quick release of said latching means from said catching means for quick separating movement between said wringer-rolls, and limiting means for limiting said separating movement.
6. In a wringer, the combination of a break-down frame for the wringer comprising a plurality of frame-parts including upper bearing means and lower bearing means, wringer-rolls comprising shafts in said bearing means, means for adjusting the distance between said upper bearing means and said lower bearing means, pivot means between said frame-parts whose pivotal axes are substantially parallel with the axes of said bearing means, one of said frame-parts comprising bow-springs as part of its frame-structure for exerting pressure between said wringer-rolls, said bow-springs located between said pivot-means and said bearing means for said one of said frame-parts, said pivot means being at one side of said wringer-rolls, said one of said frame-parts provided with extensions reaching between and to the other side of said shafts where they are provided with catching means, and latching means at said other side of said shafts coacting with said catching means for holding said frame-parts in operative relation, and quick releasing means for said latching means for quick release of said latching means from said catching means for quick separating movement between said wringer rolls.
7. In a wringer, the combination of a lower wringer roll, an upper wringer roll, a lower frame part and an upper frame part between which said wringer rolls are located, pressure means between said frame parts for exerting pressure between said wringer rolls, and means for quick release of said pressure means comprising a latching member movable pivot-wise laterally from a point on said lower frame part lower than the axis of rotation of said upper wringer roll, said latching member extending upwardly from said point, and manually operated means acting on said upwardly extending portion of said last-named member in release direction.
8. In a quick release means in a wringer, the combination of a lower frame part, an upper frame part, complementary wringer rolls operatively located between said frame parts, an upwardly extending leaf spring having attachment below its upper portion with said lower frame part, latching means above said attachment between said upper portion of said leaf spring and said upper

frame part, and a manually operated part for releasing said latching means.

9. In a quick release means in a wringer, the combination of a lower frame part, an upper frame part, complementary wringer rolls operatively located between said frame parts, an upwardly extending leaf spring having attachment below its upper portion with said lower frame part, latching means above said attachment between said upper portion of said leaf spring and said upper frame part, and manual releasing means for said latching means comprising a manually operated part and a cam.
10. In testimony whereof, I have hereunto signed my name.

GUSTAVE H. JANTZ.
